UNITED STATES PATENT OFFICE.

ROGER BOSTICK, OF BENOIT, MISSISSIPPI, AND WILLIAM E. WOODSON, OF JACKSON, TENNESSEE, ASSIGNEES OF ONE-THIRD TO J. Y. FAUNTLEROY, OF NEW ORLEANS, LOUISIANA.

RAILWAY-MAIL DELIVERY AND RECEIVING APPARATUS.

Application filed October 22, 1923. Serial No. 670,204.

To all whom it may concern:

Be it known that we, (1) ROGER BOSTICK and (2) WILLIAM E. WOODSON, citizens of the United States, residing at (1) Benoit, (2) Jackson, in the counties of (1) Bolivar, (2) Madison, and States of (1) Mississippi, (2) Tennessee, have invented certain new and useful Improvements in Railway-Mail Delivery and Receiving Apparatus, of which

10 the following is a specification.

The invention relates to railway mail delivery and receiving apparatus and particularly to apparatus of the collapsible type.

An object of the invention is to provide 15 railway mail delivery and receiving apparatus which will eliminate wear and tear on mail sacks; which will leave a maximum clearance along the right of way and which will simultaneously deliver and receive a 20 mail pouch.

These and other objects of the invention which will be apparent from the following 25 description are attained in the embodiment of our invention which is shown in the accompanying drawings, in which

Fig. 1 is an elevation of the mail crane and the cooperating apparatus on a mail car; the dotted lines illustrating the parts in collapsed or partly collapsed positions;

30 Figs. 2 and 3 are fragmentary elevations on a larger scale of the collapsible framework of the mail crane, and of the mail car apparatus, respectively;

Fig. 4 is a fragmentary horizontal section 35 showing the lower member of the mail crane framework, the section being taken on line 4—4 of Fig. 2;

Fig. 5 is a similar section, but on a smaller scale, and shows the catcher arms of the 40 mail crane;

Fig. 6 is a vertical section showing the mounting of the ring supporting plate of the mail crane, the section being taken on line 6—6 of Fig. 2;

45 Fig. 7 is a plan view of the catcher arm on the mail car, the arm being illustrated in extended position;

Figs. 8 and 9 are detail views of the 50 catcher arm clamp, Fig. 8 comprising a plan view of the clamp, and Fig. 9 a section as taken on line 9—9 of Fig. 8;

Fig. 10 is a fragmentary rear elevation of the ring supporting plate of the mail car apparatus; and

Fig. 11 is a fragmentary end elevation of 55 the mail car ring plate.

As shown in the drawings the mail crane includes a vertical standard 1 carrying T-shaped fittings 2, 3 to which the substantially parallel rods 4 and 5 of the mail sack 60 supporting framework are pivoted. A yoke 6 which is fixed to the standard 1 below the pivotal support 3 provides a pivotal support for the plate 7 to which the oppositely directed catcher arms 8 having spring 65 catches 9 fixed thereon are secured.

The parallel motion linkage is completed by a ring-supporting plate 10 which is pivoted to the rods 4, 5, and a bar or rod 11 which is pivoted to the rod 5 and to a pair 70 of rods 12 which are carried by the plate 7. The pivotal connections at the opposite ends of the rod 11 may be of any suitable type, but the pivotal connections of the ring-supporting plate 10 are designed to permit the 75

rotation of the plate 10 into a position parallel to the right of way when the framework is in collapsed position. At its inner edge and near the upper and lower faces, the plate 10 is recessed to receive sleeves 13, 14, 80 respectively, which are mounted upon pins 15, 16, respectively. The rear face of upper sleeve 13 carries a horizontal pin 17 which is journaled in a lug 18 depending from the upper rod 4, and the sleeve 14 has 85 an ear 19 depending from the inner side thereof which is pivoted to a member 19' on the lower rod 5. As viewed in Figs. 1 and 2, the rod 4 is arranged slightly to the rear of the rod 5 to permit the folding of the 90 framework close to the standard 1. A combined torsion and compression spring 20 which is arranged about the pin 16 and between the upper face of the sleeve 14 and the plate 10 tends to rotate the plate 10 95 from the full line position shown in Fig. 1 into the position shown in dotted lines, i. e. parallel to the right of way.

The lower face of the plate 10 is recessed at 21 to conform to the upper surface of the 100 rod 5, and the pin 16 of plate 10 is slidable through the sleeve 14 to bring the plate 10

into engagement with the rod 5 when the weight of a mail sack overcomes the force of the spring 20 to depress the plate 10.

The mail sack S is not attached directly to the plate 10, but is fastened by a cord or strap which passes about the center of the sack to an ear or eyelet 22 of a ring 23, which ring is mounted in the collapsible framework. The outer edge of the plate 10 is substantially semicircular as viewed in elevation, and is provided at its lower outer edge and at one or more intermediate points with lugs 24 which are concave in cross-section to receive the ring 23. The upper bar 4 of the framework carries a similarly shaped lug 25 in position to engage the upper surface of ring 23, the lug 25 and lower lug 24 being so arranged that a line joining these lugs will lie outside of the vertical center line of a ring 26 which is mounted in the framework. When the framework is raised into position and a ring 23 carrying a mail sack is mounted in the several lugs, the weight of the sack compresses the spring 20 to bring the lower face 27 of plate 10 into engagement with the rod 5 and the weight of the sack as well as the weight of the parts of the framework tends to collapse the framework, but this folding of the framework can not take place while the ring is in place since the ring holds the outer end of rod 4 at a fixed distance from the outer end of rod 5. When the sack is removed, the framework is free to collapse by gravity and the plate 10 rotates from a position transverse to the right of way into a position parallel thereto. To permit the framework to fold into a small space, the plate 7 is preferably provided with a groove 28 in line with the rod 11 and the rod 5 is offset as at 29 near its pivotal support 3.

The catcher arm 28 which is mounted upon the mail car is approximately V-shaped, and is formed with a narrow passage or loop 29 into which the ring 23 slides when it is picked up from the mail crane, the opening into the loop 29 being normally closed by a spring catch 30 which prevents the accidental release of a ring from the catcher arm. The inner branch of the catcher arm 28 is fixed in a block 31 which is pivoted to a block 32 carried by the offset portion of a rod 33 whose aligned ends are journaled in bearings 34 on the car. The catcher arm 28 may be directed toward either end of the car by a rotation of block 31 with respect to block 32, and the inner end of the arm 28 may be held in place by any suitable form of clamping mechanism at the opposite ends of the rod 33. As shown in the drawings, each of the clamps comprises a sleeve 35 fixed to the rod 33 and carrying a recessed plate 36 to which the inner end of the catcher arm may be held by the hinged cover plate 37, which is clamped in place by a winged bolt 38. The rod 33 is free to turn

in the bearings 34, consequently the catcher arm normally drops to a vertical position by gravity. A handle 39 is provided for moving the catcher upwardly into horizontal position so that the outer end of the catcher may pass through the rings 23 which are supported upon the mail cranes along the track.

The mail sack delivery apparatus upon the mail car is supported upon a vertical standard 40 and, while similar to the collapsible framework of the mail crane, is of simpler construction due to the fact that the standard 40 is located at the inner edge of the car door framing, thus providing the desired clearance without necessitating the rotation of the ring-supporting plate 41 into a plane parallel to the right of way. The plate 41 is pivotally connected to the upper end of the standard 40 by a link 42 which is attached to the upper and inner corner of the plate by a suitable pivot pin 43, which pin also connects the upper rod 44 of the folding framework to the plate. A lower rod 45 is connected to the lower portion of the plate, and preferably the outer ends of the rods 44, 45 are provided with flat surfaces for engagement with arcuate wear strips 46 of soft metal which are carried by the plate 41. The opposite ends of the rods 44, 45 are pivotally connected to the outer ends of the parallel rods 46, 47, respectively, and are joined to each other by a rod 48 whose pivot points are located close to the inner ends of the rods 44, 45, respectively. The inner ends of the rods 46, 47 are pivoted to the standard 40, which forms the fixed member of the collapsible frame which may be extended by depressing the handle 49 formed by an extension of the upper rod 46 beyond the standard 40.

To secure the simultaneous movement of the catcher arm 28 and the sack delivering mechanism, the handles 39 and 49 are joined by a link 50, and for convenience in moving the framework into extended position the link 42 is provided with a hand-grip 51.

The plate 41 carries a plurality of fixed lugs 52, and a movable lug 53 which is slidably mounted in the upper part of the plate and is urged into downward position by spring means, such as the lever 54 and leaf spring 55. Obviously the mail crane plate 10 and the mail car plate 41 are designed to support rings of identical construction, but for convenience of description the ring which is mounted in the mail car plate is identified by the numeral 56 and the sack which it carries is designated at S'.

To set the mail crane in operative position, the rods 4 and 5 are raised into substantially horizontal position and the plate 10 is rotated into alignment with the rod 5. A ring 23 carrying a sack S is then engaged in the lugs of the plate 10, and the lug 25 on the

end of rod 4, thus locking the framework in extended position. The depth of the recesses in the faces of the lugs is so designed that the ring will not be forced out of position by the wind pressure set up by a moving train or other causes, and the ring will resist all pressures except the substantially lateral pressure of the catcher arm on a passing train. The catcher arms 8 of the mail crane are moved up into operative position as the sack-delivering framework is raised, since the link 11 connects the lower rod 5 and the rods 12 of the plate 7.

A ring 56 carrying a sack S' may be engaged in the lugs of the plate 41 without first moving the framework into extended position, and then as the car approaches the mail crane the sack-delivering framework and the catcher arm 28 are extended by a downward pressure upon handles 39 or 49, and an outward thrust on the hand-grip of the link 42. As the mail car passes the mail crane, the catcher arm 28 of the car removes the ring 23 from the mail crane, and one of the catcher arms 8 of the mail crane removes the ring 56 from the mail car apparatus. When the ring 23 is removed from the mail crane the framework collapses by gravity and the plate 10 is rotated by the spring 20 into a plane parallel to the right of way, the parts taking the position shown in dotted lines in Fig. 1. When the ring 23 has been caught by the catcher arm on the mail car, the attendant releases the pressure upon the handles and this framework also collapses by gravity, an intermediate position of the framework as it folds towards the car being shown in dotted lines in Fig. 1. When the framework is fully collapsed the catcher arm 28 is in vertical position and the ring 23 and attached sack may be easily removed.

It will be noted that the setting of the mail crane and of the sack-delivering apparatus upon the mail car is not dependent upon the direction of train travel, and that no damage will result even though a train approaches from the direction opposite to that expected. It is necessary, of course, that the catcher arm upon the car be properly set according to the direction of train travel, but with this exception the setting of the apparatus is unchanged. The apparatus, both at the station and upon the train folds by gravity into inoperative position, thus preventing accidental movement of the apparatus into position across the right of way.

It will be apparent that the invention is not limited to the specific embodiment herein described since various changes may be made in the several parts, their relative size, shape and arrangement, without departing from the spirit of our invention.

We claim:

1. In a railway mail transferring apparatus, a collapsible parallel-motion framework lying substantially in a plane perpendicular to the right of way, said framework comprising a standard, rods pivoted to said standard, a ring receiving member, and pivotal connections between said member and each of said rods completing said parallel-motion framework. 70

2. Railway mail transferring apparatus as claimed in claim 1 in which said pivotal connections permit rotation of said member into a plane substantially parallel to the right of way. 75

3. A railway mail transfer device comprising a standard, rods pivotally connected to said standard, a member pivoted to each of said rods and cooperating therewith and with said standard to form a parallel-motion framework lying substantially in a plane perpendicular to the right of way, and means on said member for supporting a ring to which a mail sack may be attached. 80 85

4. A mail crane comprising a standard, a collapsible framework comprising a plurality of rods pivoted to said standard and means pivotally connecting the said rods to each other, means on said framework for receiving a sack-carrying ring, and means operative to lock the said parts of said framework against relative pivotal movement so long as a ring is positioned in said ring-receiving means. 90 95

5. In a railway mail transferring apparatus, the combination with a collapsible parallel-motion framework lying substantially in a plane perpendicular to the right of way, said framework comprising a standard, rods pivoted to said standard, and a member pivoted to each of said rods, of means on said framework for receiving a sack-carrying ring said means when engaged by a ring operating to maintain said framework in extended position. 100 105 110

6. In a railway mail transfer device, a plurality of elements having recessed faces adapted to receive a sack-carrying ring and to support the same in a plane substantially normal to the right of way, the recessed faces of said elements being arranged to engage the periphery of a ring at spaced points located along more than one-half the circumference of the ring, and an extensible framework carrying said plurality 115 120 125 of elements.

7. A railway mail transfer device comprising a plate-like member having lugs projecting from one edge thereof, said lugs having recessed faces for yieldingly holding a sack-carrying ring substantially in the plane of said plate-like member, a collapsible framework for positioning said member and a ring carried thereby in a plane normal to the right of way, and means per- 130

- mitting said plate-like member to move into a plane substantially parallel to the right of way upon the removal of the ring from said lugs.
- 5 8. A railway mail transfer device comprising a standard, a pair of rods pivoted to said standard, a plate-like member pivoted to each of said rods at intermediate points thereof to provide a parallel motion 50 framework, recessed portions at the outer edge of said plate-like member providing a seat for a sack-receiving ring, and a lug at the end of the upper rod of said pair of rods and adapted to bear upon a ring seated when a ring is positioned in said member.
- 10 9. In a railway mail transfer device, a plurality of grooved ring receiving elements and supporting means therefor, and means for maintaining said elements substantially in a plane normal to the right of way so long as a ring is positioned within the grooves of said elements, said ring-receiving elements and supporting means permitting the removal of said ring by a 55 catcher arm approaching from either direction.
- 15 10. In a railway mail transfer apparatus, a standard, a pair of spaced rods pivoted to said standard, a member adapted to receive a sack-carrying ring, and connections between said member and each of said rods permitting the movement of said rods from extended position across the right of way into vertical position along said standard and permitting the rotation of said member from an operative position transverse the right of way into an inoperative position parallel thereto, and means operative by a ring placed in said member to lock said rods in extended position and said member in operative position.
- 20 11. In a railway mail transferring apparatus, a pair of substantially parallel supporting rods, a ring-receiving member pivoted to said rods by connections which permit a sliding movement of said member, cooperating surfaces on said member and one of said rods for preventing rotation of said member when at one limit of its range of sliding movement, and yielding means urging said member away from locking position and tending to rotate said member from a position substantially in the plane of said rods to a position normal to the plane of said rods, said member being movable into locking position against the force of said yielding means by a sack-carrying ring positioned in said member.
- 25 12. In a railway mail transferring apparatus, a standard, a member adapted to receive a sack-carrying ring, a link pivoted to said member and to said standard, and a parallel-motion linkage carried by said standard and connected to said member.
- 30 13. In a railway mail transferring apparatus, a pair of spaced rods pivoted to said standard, a member adapted to receive a sack-carrying ring, and connections between said member and each of said rods permitting the movement of said rods from extended position across the right of way into vertical position along said standard and permitting the rotation of said member from an operative position transverse the right of way into an inoperative position parallel thereto, and means operative by a ring placed in said member to lock said rods in extended position and said member in operative position.
- 35 14. In a railway mail transferring apparatus, a standard, a member adapted to receive a sack-carrying ring, a link pivoted to said member and to said standard, and a parallel-motion linkage carried by said standard and connected to said member.
- 40 15. In testimony whereof, we affix our signatures.

ROGER BOSTICK.
WILLIAM E. WOODSON.
